US00D997209S

(12) **United States Design Patent** (10) Patent No.: **US D997,209 S**
 Bjerke et al. (45) Date of Patent: **** Aug. 29, 2023**

(54) **BUCKET SHROUD**

- (71) Applicant: **Caterpillar Inc.**, Peoria, IL (US)
 (72) Inventors: **Nathan R. Bjerke**, Peoria, IL (US);
Thomas M. Congdon, Dunlap, IL (US)
 (73) Assignee: **Caterpillar Inc.**, Peoria, IL (US)
 (**) Term: **15 Years**
 (21) Appl. No.: **29/843,753**
 (22) Filed: **Jun. 23, 2022**

Related U.S. Application Data

- (63) Continuation of application No. 29/775,799, filed on Mar. 25, 2021, now Pat. No. Des. 959,505.
